TOY REVOLVER

Edmund W. Baggott, Brooklyn, N. Y., assignor to
Ideal Novelty & Toy Co., Hollis, N. Y., a corpora-
tion of New York

Application October 24, 1946, Serial No. 705,455

2 Claims. (Cl. 46—9)

1

This invention relates to a toy revolver of simple and improved construction.

An object of the invention is the provision of a toy revolver which will produce intermittent noises and intermittently expel visible masses of finely divided solid material, such as talcum powder or the like, in simulation of an explosive discharge.

Another object of the invention is the provision of a sturdy and durable device of the character indicated, which can be easily fabricated at low cost from a minimum number of parts.

For the attainment of the above objects as well as such additional objects and advantages as may hereinafter appear or be pointed out, I have illustrated a preferred embodiment of the invention in the accompanying drawing, wherein:

Fig. 1 is a side elevation, partially in section of a toy revolver embodying the features of the invention;

Fig. 2 is a fragmentary view, partially in section, of the barrel portion of the toy revolver and showing the operative position of the internal parts when the revolver is discharging a mass of finely divided material in simulation of an explosion;

Fig. 3 is an enlarged sectional view taken along line 3—3 of Fig. 1;

Fig. 4 is a side elevation with parts broken away of the magazine assembly for holding a charge of finely divided solid material.

The component parts of the device, with the exception of certain metal parts, can be conveniently molded from any suitable plastic material.

The body of the device comprises a forward barrel 10, an intermediate cylinder-retaining portion 11, and a rear hand-grip portion 12.

A cylinder 13 is rotatably mounted within a cavity in the cylinder-retaining portion 11 on a spindle 14, which is secured to the body of the device. The outer peripheral wall of cylinder 13 is cylindrical except for the external longitudinal grooves 15. The forward face of cylinder 13 is provided with a plurality of internal recesses 16 extending inwardly therefrom. Any convenient number of recesses 16 may be provided in the forward face of cylinder 13 and the recesses 16 are angularly spaced by equal angles. In the particular embodiment illustrated, there are six internal cylinder recesses 16 in the forward base of the cylinder 13 and the angular spacing of said recesses is 60°.

The device is provided with a hammer 17 actuated by a trigger 18. The trigger 18 may be pivotally attached to the body of the device at the

2

lower edge of cylinder-retaining portion 11, beneath the cylinder 13, and the rotation of said cylinder is effected by the trigger 18. Any suitable arrangement may be used to effect such rotation of cylinder 13, it being understood that such arrangement does not form a part of the subject matter of the present invention, for which reason the illustration of the cylinder-rotating arrangement has been omitted in the accompanying drawing.

The barrel 10 of the device has a longitudinal bore 19 extending therethrough from the front of barrel 10 to the cavity in cylinder-retaining portion 11 within which cylinder 13 is rotatably mounted.

A plunger 20, having an enlarged rounded head 21, is slidably mounted for reciprocating motion within bore 19 by means of an internal lug or eye 22 which is integral with barrel 10. The front end of a compression spring 23, interposed between eye 22 and head 21, abuts the eye 22 and the rear end of spring 23 abuts the inner shoulder of enlarged head 21 of plunger 20, thereby biasing plunger 20 rearwardly until its head 21 contacts the front face of cylinder 13.

Each internal cylinder-recess 16 is successively located and temporarily held in the top position shown in Fig. 1, in which the longitudinal axis of the respective internal top cylinder recess 16 is coincident with the longitudinal axis of plunger 20 and plunger head 21. Since plunger head 21 as well as plunger 20 is rearwardly biased by the compression spring 23, the convex rear face of said plunger head 21 acts as a detent and yieldingly holds the cylinder 13 against rotation.

As cylinder 13 is rotated by an appropriate actuating means such as trigger 18, the plunger head 21 is moved forwardly and longitudinally to overcome the tension of compression spring 23, until said plunger head 21 clears the respective proximate internal cylinder-recess 16 and said plunger head 21 abuts the intervening, unrecessed portion of the forward face of cylinder 13, between two adjacent internal cylinder-recesses 16. At this point of the operation the forward tip of plunger 20 is carried to the forward limiting position of its reciprocating motion to strike against the magazine assembly 24, which is located at the forward end of the longitudinal bore 19 of barrel 10, and expels a small portion of the mass of finely divided solid material stored within said magazine assembly in simulation of an explosion, as illustrated in Fig. 2.

As the next internal cylinder recess 16 approaches the top position, the plunger head 21 is

forced by the compression spring 23 into the respective proximate recess 16, simultaneously locating said recess in proper position and yieldingly holding the cylinder 13 against rotation until the operator desires to repeat the cycle of operation.

The magazine assembly 24 may conveniently include a hollow and rigid cylindrical sleeve 25 having an external flange or lip 25a for locating said sleeve at the mouth of the longitudinal bore 19 of barrel 10. The rear portion 25b of said sleeve 25 may have a reduced external diameter to receive the open end of an elongated compressible receptacle or sac 26 of rubber or similar material. This sac is filled with any finely divided solid material, such as talcum powder or the like. The open end of sac 26 fits closely over the reduced rear portion 25b of sleeve 25 to provide an airtight seal and additional means, such as adhesive, may be used to produce this seal. A cap 27, which has a hollow stem 27a of such outer diameter as to produce a tight, frictional fit within hollow sleeve 25, may be used to complete the magazine assembly 24. The front wall of cap 27 has a small, central aperture 27b to allow access of a portion of the finely divided material which is stored within sac 26 to the atmosphere under the impact of plunger 20 as described above.

Magazine assembly 24 may be fixed adhesively or in any other suitable manner within the front end of longitudinal bore 19 of barrel 10. External flange 25a on sleeve 25 facilitates rapid assembly by limiting and locating the position of said sleeve 25 with respect to the front end wall of barrel 10. The front face of cap 27 is preferably of larger diameter than flange 25a and may be provided on its inner side with an annular recess 27c to fit over said flange 25a to produce an airtight seal. The rim of cap 27 may be knurled to assure easy removal and replacement of said cap 27 when it is necessary to recharge the sac 26 with finely divided material.

Since certain additional modifications may be made in the device of my invention without departing from the scope thereof, it is intended that all matter contained in the foregoing description and shown in the accompanying drawing be interpreted merely as illustrative and not in a limiting sense.

I claim:

1. A toy revolver comprising a longitudinal hollow barrel which has a mouth at its front end,

a cylinder located at the rear end of said barrel, said cylinder being turnable about a longitudinal axis, means for turning said cylinder, said cylinder having a front wall which is provided with longitudinal concave recesses which are angularly separated by planar portions of said front wall, said barrel having an internal member between said mouth and said cylinder, said internal member having a longitudinal bore, a longitudinally slidable rod which extends longitudinally through said bore, said rod having a head at its rear end, a compression spring coiled around said rod between said internal member and said head and biasing said head against said front wall of said cylinder, said head having a rear convex wall which interfits with said recesses so that the turning of said cylinder longitudinally reciprocates said rod, a resilient sac adapted to contain a finely divided substance located in said barrel forwardly of said rod, said sac having an open mouth-portion at its front end, a rigid and sleeve-like mouth-piece fitted in said mouth-portion and also in the front end-portion of said barrel, an internal hollow stem member fitted frictionally in said mouth-piece and which has a flange which externally abuts the front end-wall of said barrel, said sac being dimensioned so that said flange holds said sac in position to be compressed by said rod when said rod is moved longitudinally forwardly, whereby a portion of the contents of the sac is expelled from the front end of said barrel to simulate smoke issuing therefrom.

2. A toy revolver according to claim 1, in which the internal wall of said hollow barrel is cylindrical and said sac is cylindrical and fits closely against said cylindrical wall save at the rear end of said mouth-piece, said sac having an internal rib at said rear end of said mouth-piece.
